UNITED STATES PATENT OFFICE.

THOMAS J. MCTIGHE, OF NEW YORK, N. Y.

ELECTRICAL CONNECTOR AND METHOD OF MAKING SAME.

SPECIFICATION forming part of Letters Patent No. 650,862, dated June 5, 1900.

Original application filed February 27, 1900, Serial No. 6,713. Divided and this application filed March 30, 1900. Serial No. 10,839. (No model.)

To all whom it may concern:

Be it known that I, THOMAS J. MCTIGHE, a citizen of the United States, residing at New York, in the county of New York and State of New York, have invented certain new and useful Improvements in Electrical Connectors and Methods of Making the Same; and I do hereby declare the following to be a full, clear, and exact description of the invention, such as will enable others skilled in the art to which it appertains to make and use the same, this application being a division of my application, Serial No. 6,713, filed February 27, 1900.

This invention relates to a novel method of splicing or connecting electrical conductors, whereby two sections of conductor of any carrying capacity can be expeditiously and permanently spliced together, forming a compact and solderless joint of lower resistance per unit of length than the conductor itself and having all the mechanical strength required.

The invention consists in the novel method of splicing electrical conductors by swaging and cold-welding and in the novel character of splice or joint produced thereby, both as hereinafter fully described, and set forth in the claims.

In the accompanying drawings, which form part of this specification, Figure 1 is a side elevation of the ends of two conductor-sections with my splicing-sleeve in section prior to compression. Fig. 2 is an end view of the same, showing a pair of compressing-dies ready for application of pressure. Fig. 3 is a similar view to Fig. 1, showing the completed joint after powerful compression. Fig. 4 is an end view of Fig. 2, but with the dies brought nearly together. Fig. 5 is a side view, partly sectional, showing a modified form of sleeve before compression. Fig. 6 is a similar view after compression; and Fig. 7 is a side view, partly sectional, of a completed joint of modified character.

Referring to the drawings, my invention is carried out in the following manner: I square off the ends A B of the conductor-sections which are to be spliced, strip the insulation (if any) for a few inches, clean the ends, and insert them in a sleeve C, of ductile metal, with clean inner surface. The cross-section is preferably oval outside, as in Fig. 2. I

then inclose the sleeve C and conductor ends A B between suitable dies D D and apply a powerful pressure to the latter, tending to bring them together, as at Fig. 4. The sleeve 55 C yields under the pressure, becoming smaller in diameter and thicker in the wall, while the pressure is transmitted inwardly upon the conductor ends A B, forcing them into a compact mass—that is, the great pressure brings the 60 sleeve and inclosed conductors into a practically-homogeneous mass, the contacting surfaces of which are coherent, an effect which I call "cold-welded." In the joint shown at Figs. 3 and 4 the sectional area of the sleeve is 65 nearly double that of the conductor, while the area of surface contact between each conductor end and the sleeve is more than ten times the sectional area of the conductor. This gives a joint of extreme low resistance electrically. Mechanically, such a splice has great 70 strength. The compression hardens and stiffens the metal, and the tensile strength of the joint is ample for ordinary service.

By my invention I accomplish the splicing 75 in a few moments, remove but a few inches of insulation, and use no solder or heat. The operation is the same for all sizes of conductors. Any convenient or suitable source of pressure is applicable, such as hydraulic or 80 screw press or a wedge-press. I, however, prefer the hydraulic jack-press, which while capable of giving great pressures is still quite portable and can be carried readily along the line of work for coupling the conductor-sections. 85

Where great tensile strength is required in the splice, I so shape the sleeve C that when the pressure is applied it produces one or more peripheral constrictions in the conductors and corresponding projections on the sleeve, preventing the conductors from being pulled out. In Figs. 5 and 6 I show a specific form of such splice. The sleeve C is formed with the external beads e, and the dies D D, 95 having plain surfaces, force these ribs inwardly until the sleeve is caused to project on the inside, as at e', and thus produce one or more constricted points f on the conductors A B, as shown in Fig. 6. A similar effect is 100 produced in Fig. 7, where the outer dotted lines show the original form of the sleeve, the

full lines show the compressed sleeve and conductors, and the inner dotted lines show the constricted and compacted conductors, the same letters of reference being used as in Figs. 5 and 6 and indicating the same general idea. In Fig. 7, however, I leave the abutting ends of the conductors A B practically uncompressed, thus adding to the strength by having a relatively-deep constriction between the compacted zone and the inner end of each section.

Without exceeding the pressure easily obtainable with portable apparatus quite suitable for linework I can by my invention in a few minutes complete a splice on the largest conductor.

I claim—

1. The method of splicing electrical conductors, which consists in inclosing the ends of the conductors in a ductile metal sleeve and subjecting the same to sufficient lateral pressure to cold-weld the contacting surfaces together.

2. The method of splicing solid electrical conductors consisting in inserting the conductor ends into a ductile metal sleeve and cold-swaging the sleeve and inclosed conduc-

tors so as to reduce the cross-sectional area of the sleeve and conductors.

3. The method of splicing electrical conductors, which consists in inclosing the ends of the conductors in a ductile metal sleeve having suitably-shaped projections, and then swaging down the sleeve and conductors so as to reduce their cross-sectional area and produce at their contacting surfaces interlocking projections and depressions.

4. A splice for electrical conductors, consisting of a ductile metal sleeve inclosing the ends of the conductor-sections and cold-welded thereto.

5. A splice for electrical conductors, consisting of a ductile metal sleeve inclosing the ends of the conductor-sections and cold-welded thereto, the contacting surfaces of the conductors and sleeves having swaged interlocking projections and depressions.

In testimony whereof I have affixed my signature in presence of two witnesses.

THOMAS J. McTIGHE.
